UNITED STATES PATENT OFFICE.

WENDELL L. SHEPARD, OF WATERBURY, CONNECTICUT.

DESIGN FOR A CYCLOMETER-CASE.

SPECIFICATION forming part of Design No. 26,977, dated April 27, 1897.

Application filed March 12, 1897. Serial No. 627,251. Term of patent 7 years.

To all whom it may concern:

Be it known that I, WENDELL L. SHEPARD, a citizen of the United States, residing at Waterbury, in the county of New Haven, 5 State of Connecticut, have invented a certain new and original Design for a Cyclometer-Case, of which the following is a description, reference being had to the accompanying drawing and to the letters of reference marked 10 thereon.

My invention relates to a design for a cyclometer-case, and especially to the shape and configuration of the barrel, which contains the operating parts, and the support therefor.

15 The design is illustrated in the accompanying drawing, which is a perspective view of the invention.

In the drawing, A represents the cylinder or barrel, within which the usual numbering- 20 cylinders (not shown) are supported, this cylinder being slotted to receive a glass, and

having upwardly and outwardly extending flanges *a* adjacent the ends of the slot. Depending from the lower part of this cylinder are ears, between which is arranged and supported the upper end of a downwardly-projecting piece C, which at a point just below the ears is formed with a twisted portion *c*, so that the lower part D, which is adapted for attachment to the axle of the bicycle-wheel 30 or to any suitable part of the frame, stands at a right angle to the longitudinal axis of the cylinder.

I claim as my invention—

The design for a cyclometer-case, substantially as shown and described.

In testimony whereof I affix my signature in presence of two witnesses.

WENDELL L. SHEPARD.
